(57) **CLAIM**

The ornamental design for a robot caster, as shown and described.

DESCRIPTION

1. Robot caster
- 1.1 : Perspective
- 1.2 : Perspective
- 1.3 : Front
- 1.4 : Back
- 1.5 : Left
- 1.6 : Right
- 1.7 : Top
- 1.8 : Bottom

A robot caster is applied to a walking end of a robot, a foot walking of a robot, etc.; it can be used in the fields of service robots, medical robots and industrial robots; the broken lines in the drawings depict portions of the robot caster that form no part of the claimed design.
